(57) **CLAIM**

The ornamental design for a weight collar for a weight lifting bar, as shown and described.

DESCRIPTION

FIG. 1 is front view of a weight collar for a weight lifting bar; FIG. 2 is a perspective view thereof;

FIG. 3 is a left side view thereof;

FIG. 4 is a right side view thereof;

FIG. 5 is a bottom view thereof; and,

FIG. 6 is a top view thereof.

The broken lines in FIG. 4 illustrate environmental structure and form no part of the claimed design.
